UNITED STATES PATENT OFFICE

FRANK T. COPE, OF SALEM, OHIO, ASSIGNOR TO THE ELECTRIC FURNACE COMPANY, OF SALEM, OHIO, A CORPORATION OF OHIO

HEAT TREATING CONTAINER

Application filed March 19, 1930. Serial No. 437,058.

The invention relates to containers adapted to accommodate metal objects during heat treatment, and more particularly to a container designed for use when it is desired to heat the objects in contact with a suitable gas.

The use of gases in various kinds of heat treatment of metals is well known and the purpose of the gas may be to prevent oxidation, as in annealing, in which case a neutral or reducing gas may be used; or to cause absorption of a hardening agent by the surface of the objects under treatment, as in carburizing, wherein a gas containing the said hardening agent in available form may be used.

In carrying out heat treatments of this nature it is usually undesirable, and frequently very detrimental to the material under treatment, to permit access of air, or other gases such as may be encountered in a furnace, to the interior of the container.

It is, however, necessary to provide means for opening the container in order to charge and empty the same, and some form of seal for said opening is therefore necessary.

If such seal is not substantially gas tight it will result in the consumption of an excessive quantity of gas; danger of explosion 30 when a combustible gas is employed; or discomfort or injury to persons working around the furnace when a noxious or poisonous gas is used in the heat treatment.

It is common practice to use gaskets and packings for sealing such containers, but such means does not provide a seal which remains effective due to warping or distortion of the component parts by exposure to the high temperatures under which the heat 40 treatments are carried out.

Furthermore, such seals usually require bolts or other clamping means which are laborious and often difficult to operate and which frequently prevent opening of the container as rapidly as may be desirable or necessary after completion of the treatment.

Sand and clay have long been used in an effort to effect the sealing of containers in various treatments but such sealing means at 50 best only hinder and do not prevent diffusion

between the gas within the container and the furnace atmosphere and are not sufficiently effective to permit the employment of any appreciable excess of pressure within the container as compared with the furnace atmos- 55 phere.

The object of the present improvement is to provide a container having a sealing means which eliminates bolting, clamping or the like, thus permitting a container to be readily 60 and easily opened and closed when desired.

A further object is to provide such a sealing means, the effectiveness of which is not impaired by warping or distortion of the parts of the container under high tempera- 65 tures.

Another object is to provide a seal of this character which effectively prevents any diffusion between the gas within the container and the furnace atmosphere; and to prevent 70 any appreciable leakage of gas through the seal in order that pressures somewhat higher than atmospheric may be maintained within the container.

A still further object is to provide means 75 whereby fresh gas may be introduced into the container as required and spent gas removed therefrom during the heat treatment without permitting access of the atmosphere to the container.

The above and other objects may be attained by constructing the container of two or more parts with a separable joint therebetween lying substantially in a horizontal plane, said joint being surrounded with a 85 trough or channel of suitable depth and containing a suitable sealing material, the cover member of the container having a depending flange adapted to enter the trough or channel 90 and to be imbedded in the sealing material.

For the purpose of supplying gas to the container, a pipe or conduit may communicate therewith and a second pipe or conduit may be provided therein for conducting spent gas away from the container to any desired point, means such as a throttling valve or the like being provided in the discharge pipe for permitting the gas to be maintained under pressure within the container.

I have found that a satisfactory sealing material consists of mineral matter having a density substantially greater than that of silica sand, and so pulverized as to have a 5 large proportion thereof substantially as fine as possible.

Very satisfactory results may be attained by using chromite or chrome-iron-ore, which has a density about 4.5 times that of water, 10 as compared with silica sand having a density about 2.6 times that of water. Other materials suitable for this purpose are corundum having a specific gravity of approximately 4.4, and hematite with a specific gravity of approximately 15.

An embodiment of the invention is illustrated in the accompanying drawing, in which

Figure 1 is a vertical sectional view 20 through a furnace, showing the improved heat treating container therein;

Fig. 2, an enlarged fragmentary sectional view through the sealed joint between the container and cover;

Fig. 3, a similar view of the sealed joint between the base and side wall of the container; and

Fig. 4, a view similar to Fig. 2 of a modified form of seal.

Similar numerals refer to similar parts throughout the drawing.

The improved heat treating container to which the invention pertains may be located 35 within a furnace of any type suitable to the treatment which is to be carried on.

As shown in the drawing, the furnace may comprise the bottom wall 10 and side walls 11 mounted upon any suitable structural base 40 as indicated generally at 12, and enclosed within a metallic shell 13.

A removable roof 14 is adapted to rest upon the upper edges of the side walls and a sand seal is preferably provided between 45 the roof and side walls, as indicated generally at 15.

The interior of the furnace may be heated by any suitable means such as the electrical resistors 16 and means may be provided in 50 the bottom of the furnace, such as the pier 17, for supporting the improved container to which the invention pertains, illustrated generally at 18.

The improved container may comprise the 55 base 19, side wall section 20 and cover 21, the base and side wall section being preferably separable, in which case a sealed joint is provided between said members.

This joint may be in the form of a channel 60 or trough 22 formed around the edges of the base 19 and adapted to receive the lower edge portion of the side wall section 20, suitable sealing material, as above described, being provided in the trough or 65 channel, as indicated at 23, so as to form a

substantially gas-tight seal between the base and side walls.

Brackets or the like, as indicated at 24, may be fixed upon the outer side of the side wall section 20 at a point near the upper end 70 thereof for supporting the channel or trough 25 containing sealing material 23.

The upper portion of the side wall section may be flared outward as at 26 and provided with the depending flange 27 adapted 75 to extend into the channel 14 and the cover 21 may have a similar depending flange 28 also extending into the channel 25 whereby a substantially gas-tight seal is provided between the upper end of the container and 80 the cover.

For the purpose of removing the cover, an eye or the like, as shown at 29, may be extended upward from the central portion thereof.

A gas supply pipe 30 may extend from any suitable source of gas supply through a wall of the furnace and communicates with the interior of the container, being preferably centrally located through the base 19, and a 90 gas discharge pipe 31 may communicate with the container, preferably extending through the upper portion of the side wall section thereof and is located through a wall of the furnace for the purpose of carrying such 95 spent gases to a suitable point outside of the furnace or even, if desirable or necessary, outside of the building in which the furnace is located.

For the purpose of maintaining a gas pressure above that of the atmosphere within the container, as well as for preventing the entrance of air to the container through the discharge pipe, a throttling valve 32, or other suitable device, may be provided in the discharge pipe.

The separate or independently movable seal channel or trough 25 is advantageous in some cases because it permits the trough to expand freely without interference from the 110 side walls 20 of the container in cases of non-uniform heating, but for many purposes the trough may be formed integral with or fixed to the side wall, as shown at 25a in Fig. 4, this trough being adapted to hold the sealing 115 material 23 and to receive the depending flange 28 of the cover in order to form a substantially gas-tight seal.

It should also be understood that the base 19 and side wall section 20 may be fixed together or formed integrally although the construction illustrated in Figs. 1 and 3 is of advantage in that it permits relative expansion of the parts while enabling a gas-tight closure between the same.

It should be understood that I may use any desired number of seals in the container and may locate the seal or seals wherever convenient. For instance, it may be desirable to form a separable joint only at the junction 130

between the side walls and the base, in which case the side walls and top may be formed integral or permanently fastened together. If desired, the side walls may be formed in 5 a plurality of sections using a seal at each junction between such sections.

From the above it will be obvious that the present improvement overcomes the objections and difficulties referred to in the present 10 practice and fulfills the objects above set forth in that it provides an efficient seal easily and readily separable when desired, by which entrance of air or other gases may be rendered impossible and outward leakage 15 substantially prevented; and which permits a considerable excess of pressure to be maintained within the container.

In practice I have found that a seal of convenient depth will retain pressures of the 20 order of four ounces per square inch, which pressures are ample for the requirements usually met in heat treating for which the container is adapted.

I claim:

25 In a heat treating container adapted to contain gas under pressure and including a separable joint, sealing means for the joint including pulverulent chromite.

In testimony that I claim the above, I have 30 hereunto subscribed my name.

FRANK T. COPE.
